(57) **CLAIM**

The ornamental design for a wall-mounted showerhead, as shown and described.

DESCRIPTION

FIG. 1 is a perspective view of a wall-mounted showerhead showing our new design;

FIG. 2 is a right side view thereof, the opposite side being a mirror image of the side shown;

FIG. 3 is a top plan view thereof;

FIG. 4 is a front elevational view thereof;

FIG. 5 is a rear view thereof;

FIG. 6 is a front elevational view of an alternative embodiment thereof;

FIG. 7 is a right side view of the alternative embodiment thereof; and,

FIG. 8 is a top plan view thereof.

The broken lines of the face pattern are for illustrative purposes only and form no part of the claimed design.
